UNITED STATES PATENT OFFICE.

JOHN ALBERT JOHNSON, OF ST. PAUL, MINNESOTA, ASSIGNOR OF ONE-HALF
TO JAMES S. PIERSON, OF TREMPEALEAU, WISCONSIN.

RAILWAY-SWITCH.

SPECIFICATION forming part of Letters Patent No. 431,360, dated July 1, 1890.

Application filed December 24, 1888. Serial No. 294,463. (No model.)

To all whom it may concern:

Be it known that I, JOHN ALBERT JOHNSON, a citizen of the United States, residing at St. Paul, in the county of Ramsey and State of 5 Minnesota, have invented certain new and useful Improvements in Railway-Switches, of which the following is a specification.

This invention relates to that class of railway-switches known as "three-way split switches," and it consists in the construction, combination, and arrangements of parts, as hereinafter shown and described, and specifically pointed out in the claims.

In the drawings, Figure 1 is a plan view of 15 one of the switches complete. Fig. 2 is a cross-sectional view on the line xxx of Fig. 1. Fig. 3 is an enlarged view in section on the line yy of Fig. 2, and of the switch-block, illustrating more fully its construction and 20 operation. Fig. 4 is an end view of the part shown in Fig. 3. Fig. 5 is a detached perspective view of one of the head-plates. Figs. 6, 7, and 8 are similar views of the intermediate plates, illustrating more fully their construction. Fig. 9 is a perspective view of one 25 of the bars connecting the "points" with the switch-levers and by which the points are operated.

$A' A^2$ represent the main-line rails at the 30 "tail" end of the switch, and $A^3 A^4$ represent the main-line rails at the "head" or "point" end of the switch, rails $A^5 A^6 A^7 A^8$ being placed between the ends of the main-line rails.

$A^9 A^{10}$ represent the outside switch-rails, 35 which in this form of switch are united to the point end of the main-line rails, as shown at a' and a^2 , the main-line rails at the point ends being merely bent to either side to secure the necessary curve to run upon the side 40 tracks.

A^7 represents the inner main rail of the left-hand side track, and A^6 represents the inner main rail of the right-hand side track or turn-out, and between the ends of these 45 side-track rails and the points $a' a^2$, where the rails $A^3 A^4$ are bent off to the side, are inserted the "split rails" $A^5 A^6 A^7 A^8$, formed with their sides b planed or otherwise cut off to a long taper or slanting incline, so that when 50 the points $c' c^2 c^3 c^4$ are moved over against the rails $A^9 A^{10}$ the wheels of the cars may easily run upon them, as hereinafter shown.

In the drawings the rails are shown in position to conduct the cars upon the main line, the switch-rails $A^6 A^7$ being inward, out of 55 contact with the other rails and consequently inoperative.

The tapered ends $c' c^3$ of the rails $A^5 A^7$ are connected together by tie-bar B' , and the ends of the rails $A^6 A^8$ are similarly connected 60 by a similar tie-bar B^2 , the two tie-bars provided with arms $B^3 B^4$, by which they are connected by switch-bars $B^5 B^6$ to cranks $D' D^2$ on a switch-beam or head-tie D^3 , as shown, the crank-shafts being provided with weight- 65 ed levers $E' E^2$, by which they may be operated. By throwing the lever E' over to the right and the lever E^2 over to the left, as in the drawings, the rails $A^5 A^8$ will be thrown to conduct the cars upon the main 70 line, and then by throwing both levers over to the left the rail A^7 will be thrown into contact with the rail A^8 and the rail A^5 thrown against the rail A^6 to cause the cars to be run upon the left-hand side track, and by throwing the levers over to the right the rails will be set to conduct the cars upon the right- 75 hand side track. In denoting the "left" and "right" hand tracks the observer is supposed to stand at the switch-stand or head or point 80 and be looking toward the tail of the switch.

The ends $c' c^2 c^3 c^4$ of the rails $A^5 A^6 A^7 A^8$ are so thin that when two of the thin ends are together, as they will be when set to run the cars upon either of the side tracks, the 85 extra thickness at these points will not interfere with the running of the flanges of the wheels over them. As an additional precaution, however, the rails $A^5 A^8$ are formed slightly shorter than the rails $A^6 A^7$, so that 90 at the extreme points there will only be the thickness of the two points, as in ordinary split rails. Beneath the ends $c' c^2 c^3 c^4$ of the rails $A^5 A^6 A^7 A^8$, and also beneath the rails A^9 and A^{10} , where they cross the head-tie D^3 , plates $F' F^2$ will be secured to the ties 95 by spikes or bolts, as shown.

On the plates $F' F^2$, outside the rails $A^9 A^{10}$, are riveted or otherwise securely fastened stop-plates or brace-blocks $d' d^2$, adapted to 100 partially enclasp the lower flange or base of the rails $A^9 A^{10}$ to prevent them from spreading, and upon each of the other ties G , beneath the rails $A^5 A^6 A^7 A^8$ and beneath so

much of the rails $A^9 A^{10}$ as come opposite the rails $A^5 A^6 A^7 A^8$, are placed plates H' , similar to the plates $F' F^2$, except that they are not so wide. Each of these plates H' is provided with brace-blocks e , adapted to enclasp the lower flanges of the rails $A^9 A^{10}$ to prevent them from spreading, and each plate will be formed thicker where the lower surfaces of the rails $A^5 A^6 A^7 A^8$ run upon it than the part upon which the lower surfaces of the rails $A^9 A^{10}$ rest, so that the upper surfaces of the rails $A^5 A^6 A^7 A^8$ will project above the upper surfaces of the rails $A^9 A^{10}$, as shown in Fig. 2, whereby the rails $A^5 A^6 A^7 A^8$ will receive the weight of the wheels and prevent the friction of the "double flange" on worn wheels from striking the main rails.

The rails $A^5 A^7$ and $A^6 A^8$ are connected at suitable intervals by tie-bars $K' K^2$, as in all switches of this class, to cause the rails to move in concert. These connecting-bars $K' K^2$ are above the ties G , and are adapted to rest in cavities g , formed for them in the plates H' , so that the tie-bars will not interfere with the action of the rails, while at the same time the tie-bars will be supported by the grooves g and held in place thereby. The bars will not be required upon every tie, but only upon about every other one, as shown.

The plates H' , which occur where the bars $K' K^2$ are not required, will be supplied with a groove h' , into which a plate h^2 , having an upturned end h^3 , will be secured. The upturned ends adapted to be secured against the inner surfaces of the webs of the outer rails $A^9 A^{10}$ will prevent them from being crowded inward. The upper surfaces of these plates h^2 will not project above the main surface of the plates H' , so that their presence will not interfere with the action of the rails when moved back and forth over them.

The levers $E' E^2$, as before stated, will be weighted, the weights $E^3 E^4$ being heavy enough to insure the switch being retained in whatever position it may be left without further fastening; but as a measure of precaution I have provided the inner and outer arches $E^5 E^6$, between which the levers work, with coincident holes, through which pins may be inserted to lock the switches in place, if required. The weights $E^3 E^4$ on the levers $E' E^2$, as will be observed in Fig. 2, appear as circles, and are capable of being utilized as "targets" to denote the position of the switches. When the engineer or other operator sees the two weights separated, as in Fig. 2, he will know that the switch is set for the main line, and if he sees that the two targets are eclipsed on the left he will know that the switch is set to conduct the cars to the left-hand turn-out, and if the weights both appear to be turned over to the right, or, in other words, are eclipsed on the right, he will know that the switch is set to conduct the cars into the right-hand turn-out. It

will be seen that by mounting the targets in close proximity, as I have done, the engineer is able to accurately determine at a glance the positions of the switches, for the targets are so close to each other that the foremost will always eclipse the other on the right or left hand side of the stand, according to whether the right or left hand turn-out is open, and they will only appear as two targets or separated when the through or main line is open. Thus the engineer simply has to determine whether he sees one or both of the targets, and whether, if he sees but one, it appears on the right or left hand side of the stand, and this also is the case whether the engine is approaching the switch on a curve or on a straight course, as the targets are arranged so close together that even on very abrupt curves, while they will not, strictly speaking, be totally eclipsed, yet they will be so nearly so as to afford no opportunity for doubt. Hence the targets will, for all practical purposes, appear to be completely eclipsed from any point on the track beyond the switch whenever the levers are turned in the same direction and at the same angle of inclination.

By slight modifications of the gearing the levers may be arranged to operate a semaphore or lantern for showing different-colored lights. Such a construction is shown in Figs. 1, 2, 3, and 4 consisting of two upright bars $L' L^2$, each having its respective upper end forked, as at $L^3 L^4$, or other means for securing and supporting the lamp may be supplied. The bar L' has a forked plate L^5 attached to it with its forks pointing toward the lever E' , and the bar L^2 has similar forked plate L^6 with its forks pointing toward the lever E^2 . By this means, when the lever E' is thrown over toward the left from the position shown in Fig. 3, it will come in contact with the left-hand fork of the plate L^5 and turn the bar L' one-fourth around and cause the lamp upon its upper end to be likewise turned to expose a different color than before the switch-lever was moved, and then when the switch-lever is thrown over to the right again the other fork of the forked plate will be acted upon and the bar L' turned back again one-fourth a revolution and the lamp again turned, thus exposing the requisite color toward the coming train, according to the position of the switch-rails. The other lever E^2 acts in the same manner upon the forked plate L^6 and the bar L^2 . By this means the positions of the levers $E' E^2$ and their lamps correspond, so that the switch may be employed in the night-time as well as in the day-time. The bars $L' L^2$ will be formed square near the lower ends and embraced by spring-plates $L^7 L^8$ to hold them in whatever position they may be placed.

The inner and outer arches E^5 and E^6 are formed of separate pieces and have corresponding ribs and grooves m' , by which the

parts may be easily united and the whole connected together by bolts m^2 . By this simple construction the different parts may be duplicated and easily put together, and by their peculiar form of parts cannot be put together in a wrong position, as there will be but one way in which they can be united. This feature is also true of the plates $F' F^2 H'$. The head-plates $F' F^2$ will be right and left handed, 5 hence cannot be wrongly placed, as they will only fit where they belong, and the plates H' beneath the rails $A^5 A^6 A^7 A^8 A^9 A^{10}$ will be likewise adapted only to fit the places they are to occupy, so that they cannot be placed 10 in the wrong position. Each of the plates will be numbered or otherwise marked, so that their positions can be easily determined, and the process of laying the switches thereby 15 greatly simplified.

20 I gain a great advantage in the manner of forming the plates H' of nearly the full width of the ties, as I thereby prevent the plates cutting down into the wood of the ties and causing the rails to assume an uneven position. 25 By forming the plates long enough to pass entirely beneath all of the rails upon each tie I am enabled to spike them firmly to the ties and attach the stop-plates $d' d^2 e$ by riveting, so that the rails will be firmly held 30 and prevented from spreading or getting out of line otherwise. Another advantage of the wide plates is that the spike can be inserted into the ties at greater distances apart and out of line lengthwise of the ties, so that the 35 different spikes are not held by the same section of the grain of the wood, thereby greatly increasing their holding power.

A switch very similar in some respects to the one herein described is also shown and 40 described in my application, Serial No. 328,127, filed October 25, 1889.

Having thus described my invention, what I claim as new is—

1. In a three-throw switch, the combination, 45 with the outside rails and the two sets of shiftable switch-points connected together in pairs so as to move in concert, of two operating-levers connected to their respective pairs of switch-points and being pivoted to oscillate late to and from the track, and a target carried by each lever, said levers being pivoted so close together that whenever the levers are turned in the same direction and at the same angle of inclination one of the said tar-

gets will appear eclipsed by the other from 55 any point on the track beyond the switch, substantially as set forth.

2. In a three-throw switch, the combination, 60 with the outside rails, the two sets of shiftable switch-points connected together in pairs so as to move in concert, and a switch-stand, of two upright operating-levers arranged in close proximity and pivoted in the same switch-stand on axes extending lengthwise of the track, whereby their relation to one another 65 may be readily observed from the train, rods connecting said levers with their respective pairs of switch-points, and two semaphores arranged side by side in a line transverse to the track and adapted to be actuated independently of each other by the movement of said levers, substantially as and for the purposes set forth.

3. In a three-throw switch, the combination, 75 with the outside rails and the two sets of shiftable switch-points connected together in pairs so as to move in concert, of two operating-levers arranged in close proximity and pivoted on axes extending lengthwise of the track, whereby their relation to one another 80 may be readily observed from the train, rods connecting said levers with their respective pairs of switch-points, two semaphores arranged side by side on one side of the track and in a line transverse to the track, uprights 85 upon which said semaphores are supported, and forked plates $L^5 L^6$, secured to said uprights, respectively, and each plate straddling one of the said levers, substantially as and for the purposes set forth. 90

4. In a three-throw switch, the combination, 95 with the two pairs of switch-points, of the outside arches E^5 , the inside arch E^6 , located between the arches E^5 , the switch-levers located one on each side of the inside arch between 100 it and the outer arches and having cranks D^2 journaled to oscillate transversely of the switch, rods connecting said cranks with their respective pairs of switch-points, and targets carried by the upper ends of said levers, substantially as set forth.

In testimony whereof I have hereunto set my hand in the presence of two subscribing witnesses.

JOHN ALBERT JOHNSON.
